[57] **CLAIM**

The ornamental design for the table, as shown and described.

DESCRIPTION

FIG. 1 is a top plan view of a table showing my new design;

FIG. 2 is a front elevational view;

FIG. 3 is a side elevational view, the opposite side being a mirror image thereof;

FIG. 4 is a rear elevational view;

FIG. 5 is a top plan view of a table, showing an alternative embodiment of my new design;

FIG. 6 is a front elevational view of the alternative embodiment;

FIG. 7 is a side elevational view of the alternative embodiment, the opposite side being a mirror image thereof;

FIG. 8 is a rear elevational view; and

FIG. 9 is an enlarged fragmentary view, showing the edge of the table top in greater detail.

FIG. 9

FIG. 3

FIG. 4
